UNITED STATES PATENT OFFICE.

CHARLES HENRY HAMILTON SCOTT, OF LYNCHBURG, VIRGINIA, BY CHARLES B. SCOTT, COMMITTEE, OF LYNCHBURG, VIRGINIA.

AIRSHIP.

1,183,683.

Specification of Letters Patent.

Patented May 16, 1916.

Application filed April 16, 1915. Serial No. 21,938.

To all whom it may concern:

Be it known that I, CHARLES B. SCOTT, a citizen of the United States, and a resident of Lynchburg, in the county of Campbell and State of Virginia, have been appointed committee for CHARLES HENRY HAMILTON SCOTT, of Lynchburg, in the county of Campbell and State of Virginia, who has made certain new and useful Improvements 10 in Airships, of which the following is a specification.

The invention relates to improvements in air ships, and it consists in the combinations, constructions, and arrangements herein described and claimed.

An object of the invention is to provide an air ship having a main sustaining plane formed of two sections disposed in angular relation to each other in substantially V-shaped relation with means for forcing air against the planes, the thrust of the air serving to raise the device and to sustain it.

A further object of the invention is to provide an air ship having novel means for drawing in air from the sides of the machine, these means consisting preferably of a series of fans or blowers so arranged as to operate most efficiently for the purpose intended.

A further object of the invention is to provide an air ship of the type mentioned which is provided with means for sustaining the machine or permitting its gradual descent in case of accident or injury, thereby insuring the descent of the machine 35 slowly and obviating any danger to the passengers.

A further object of the invention is to provide improved means for bracing and strengthening the air ship.

These and many other objects and advantages will appear in the following specification, and the novel features of the invention will be particularly pointed out in the appended claims.

The invention is illustrated in the accompanying drawings forming part of this application, in which:

Figure 1 is a plan view of the device. Fig. 2 is a side view. Fig. 2^a is a detail 50 view of a portion of the parachute attach-

ment. Fig. 3 is a section along the line 3—3 of Fig. 1. Fig. 4 is a detail sectional view of a portion of the parachute operating mechanism. Fig. 5 is a detail perspective view of another portion of the parachute 55 operating mechanism. Fig. 6 is a sectional view along the line 6—6 of Fig. 2, looking in the direction of the arrow. Fig. 7 is a section along the line 7—7 of Fig. 1. Fig. 8 is a section along the line 8—8 of Fig. 1. Fig. 9 is a plan view of a modified form of 60 the device. Fig. 10 is a side view of the form shown in Fig. 9. Fig. 11 is an enlarged section of a portion of the device, along the line 11—11 of Fig. 10. Fig. 12 65 is a plan view of a further modified form. Fig. 13 is a side view of the form shown in Fig. 12, and Fig. 14 is a section through a portion of the device shown in Fig. 12, along the line 14—14.

Referring now particularly to Figs. 1, 2, and 3, there is shown a frame comprising upper horizontal members 1, lower horizontal members 2, uprights 3, the frame thus constructed being braced by suitable guy 70 wires 5.

Supported by the frame is the main sustaining plane, which I term the "twin" plane, due to the fact that it consists of two portions 6 and 7 disposed in angular relation 80 so as to form substantially a V-shaped structure, as clearly shown in Fig. 3. Between the wings or sections 6 and 7 of this V-shaped sustaining plane, is disposed a platform 8 upon which are mounted the engines which 85 drive the various propellers, and fans or blowers that cause the device to rise in the air and also to propel it forwardly. Certain of these engines are for the purpose of driving the side propellers or blowers 90 and others are for the purpose of driving the end propellers. It is obviously a matter of design as to how many engines shall be used.

Consider now Fig. 3; there is shown one 95 of these engines at 10. The drive shaft of this engine is prolonged on both sides as shown at 11 and propellers or blowers 12 are mounted on the ends of the shaft 11 near the sides of the machine. It will be 100

noted that the shaft 11 passes through the sustaining planes, or rather the sections 6 and 7 of the main sustaining plane, openings being left for that purpose. The ends of the shaft 11 are journaled in the main frame.

In Fig. 2 are shown four of these propellers as being disposed along the side of the machine. These are preferably arranged in pairs, for it will be noted that the 10 propellers at the left Fig. 3, have their blades turned in one direction, while those at the right of the central line of the figure, that is to say, at the forward end of the machine, have their blades turned in the 15 opposite direction. All the propellers are designed, however, to force air from the sides of the machine toward the inclined planes 6 and 7 as indicated by the arrows in Fig. 3 and Fig. 1. Each propeller or blower 20 12 is incased in a hollow cylindrical shield 13 and above the series of propellers or blowers on both sides of the device, are protective covers 14.

At the front end of the device are extensions 15 and 16 of the shape shown in the drawings. It will be observed that these extensions are of such shape as to reduce the head resistance to a minimum. At the rear of the device is a rudder 17 which is 30 disposed centrally of the machine, while at the front is a similar rudder or guide member 18. These rudders are designed to be manipulated in the manner hereinafter described.

In Fig. 7 is shown in detail the means by which the engine 10 drives the propeller which causes a forward movement of the machine. As will be observed from this figure, the engine shaft 11 is provided with 35 a bevel gear 19 arranged to mesh with a gear 20 on a shaft 21 which is supported in bearings 22 and which passes through a casting or auxiliary bearing 23 secured to the rear part of the frame. The rear propeller 40 24 is mounted on the shaft 21. A similar arrangement obtains at the front end of the device, that is to say, there is a shaft 21 which passes through an auxiliary bearing 23 and is connected with the engine 10 at 45 one end and bears a propeller 24 precisely similar to the propeller at the rear end.

Extending downwardly from the main frame which supports the main sustaining plane, are rods 25, see Fig. 2, which support 50 the car 26. In order to further brace the car, the guy wires 27 are provided.

Disposed above the car 26 are wings or planes 28 and 29 respectively which are pivotally mounted at 30 on brackets 31 secured to the rods 25. Links 32 are pivotally secured to the wings or planes 28 and 29 and these links are in turn pivotally secured to rods 33 at each end of the car. The purpose of these wings or planes 28 and 29 is to

serve as an emergency device so that if any 65 accident should occur, as for instance, if the motors should stop, then they can be opened up so as to form a parachute and thereby permit the machine to descend slowly to the ground. In order to further assist in the 70 sustaining effect, there may be provided a structure 34 attached to the side edges of the wings or vanes 28 and 29 which will spread out like a fan so as to resist the rush of air at the sides of the wings or vanes 75 28 and 29.

The simultaneous opening of the parachute device is accomplished by the mechanism best shown in Fig. 5. From this figure it will be observed that a rock shaft 35 is 80 provided with an operating lever 36 having a locking segment 37 to hold the lever 36 in position. An arm 38 is connected to one end of the rock shaft 35 and is pivotally connected with one of the push rods 33. At 85 the other end of the rock shaft is an arm 39 connected by a link 40 with an arm 41 on a rock shaft 42 which is provided with an arm 43 pivotally connected with the other rod 33. It will thus be seen that on manipulation of the lever 36 both of the rods 33 may be raised simultaneously and to the same extent, thereby pushing upwardly on the links 32 and causing the wings or vanes 28 and 29 to assume the dotted line position 95 shown in Fig. 3, thus opposing a rapid descent and permitting the car to come down safely.

At each end of the car 26 is a drum 44, the drum at the forward end of the car being connected by means of a cable with the forward rudder 18, there being two of these cables 45 for the rudder 18, one on each side thereof. In Fig. 3 these cables 45 are shown as being carried by the main frame, and in Fig. 2 one of the cables is shown connected to the drum and to the forward part of the front rudder 18. The rear drum 44 is connected to the rear part of the rear rudder 17 by a cable 46 in precisely the same 110 manner. The rear rudder 17 is hinged at 17^a at its front end while the front rudder 18 is hinged at 18^a at its rear end. It will thus be seen that the guiding of the machine can be effected from the front or from the 115 rear.

In order to more effectively control the operation of the device, means are provided for shutting off the air forced through the casings 13 by the inclined wings 6 or 7 if the 120 machine should suddenly descend. As will be seen from Fig. 2, I provide a series of curtain rollers 47, these rollers being disposed vertically and bearing curtains which are connected with small drums disposed on vertical shafts 49 by means of flexible cords or cables 50. The shafts 49 are adapted to be driven by horizontal shafts 51 through

the medium of bevel gears, and the shafts 51 are operatively connected through bevel gears with the central shaft 52 connected with a motor 53. The latter is preferably 5 of the electric type and may be actuated by any suitable source of current (not shown) and through an ordinary switch (not shown). When the switch is closed, the motor is operated so as to draw the 10 curtains over the ends of the cylindrical casings 13, thereby shutting off the air, in the descent of the machine, as explained above.

From the foregoing description of the 15 various parts of the apparatus, the operation thereof may be readily understood.

The fans 12 are set in motion, the air is drawn in from the side as already explained, and forced against the plane sections 20 6 and 7. Since these sections are at an angle to the general direction in which the air is coming, it will be apparent that the resultant pressure may be divided into components, certain of which are opposite 25 and equal and certain of which are in a vertical direction. The components of the force which are oppositely directed of course counterbalance each other while the vertical components of the force tend to raise the 30 machine off the ground. The rapidity with which this will occur will, of course, depend upon the speed of the motor which is under control. The forward movement of the device is attained by the propellers 24 at the 35 front and rear ends of the machine, while the guiding of the device is effected by the front and rear propellers as already described.

In case there should be any reason why 40 one should quickly want to descend, this may be accomplished by closing the circuit to the motor 53 and thus closing the curtains on the rods 47. A wire netting or grating 54 is provided for closing the ends of the 45 cylindrical casings 13 so as to form a backing for the curtains when the latter are drawn to shut off the rush of air when the machine is descending.

As a measure of safety, the parachute is 50 provided which has already been described in detail. The operator of the car, by shifting the lever 36, may cause the wings or planes 28 and 29 to unfold into the dotted line position shown in Fig. 3. The car being suspended below the device so that the center of gravity is low, will cause the device to come down on an "even keel" after the manner of an ordinary parachute, so that even if the engine should stop and the 55 steering apparatus be out of order, no danger will result from the slow descent of the car due to this parachute arrangement.

In Figs. 9 to 11 inclusive, is shown a modified form of the device. In these fig-

ures it will be observed that the engines 10^x 65 drive the front and rear propellers 24 as in the preferred form of the device. Auxiliary engines 10^y drive shafts 11^x which bear fan blades 12^x, see Fig. 11. In this form of the device air is admitted through an opening 70 56 which is covered by wire netting 54^x near the top of the fan, the lower portion of the fan being protected by a side wall 57. A curtain roller 47^x is provided with a curtain which is attached by means of a flexible cord 75 50^x to a drum 58 on a shaft 59 operated by a motor 60. As will be seen from Fig. 9, there are a number of these drums on the shaft 59 so as to provide a drum 58 for each curtain. In this form of the device the 80 fan 12^x draws in the air and forces it against the inclined surfaces 6 and 7 in the manner already described.

In Figs. 12 to 14 inclusive, is shown another modified form in which engines 10^z 85 drive the front and rear propellers 24. Auxiliary engines 10^w drive shafts 61 upon which are mounted sprockets 62, see Fig. 14. These are connected by sprocket chains 63 with sprockets 64 on a shaft 65. The 90 sprocket chains bear blades 66 which are so arranged as to draw air through the opening 56, see Fig. 14, and project it against the sections 6 and 7. The remaining portions of the modified form shown in Figs. 95 12 and 14 are substantially the same as those in the other forms.

It will be seen that the invention provides a novel form of airship which is positive in action and does not depend for the lifting 100 of the device upon its forward movement through the air. Being independent of this forward movement, it can be more easily controlled. In the ordinary device, the machine must be forced forwardly at a given 105 rate or it cannot ascend; in my device, on the other hand, the ascent of the machine can be accomplished without any forward movement whatever, so that the device is especially designed for operation in which 110 the hovering of the device over a point is desired. It is thus very efficient for observation purposes during wartime.

The device is not only designed to operate as an independent structure, but a series of 115 such structures may be connected up to form a train, each with its independent lifting mechanism.

What is claimed as new is:

1. An airship of the heavier than air type 120 comprising a main frame, a main sustaining plane carried by said frame and consisting of a pair of planes arranged in angular relation so as to form a V, a series of blowers on one side of said sustaining plane, a second series on the opposite side, means for operating each of said series so as to force air inwardly and from opposite directions 125

4

toward said main sustaining plane, certain opposed fans or blowers on opposite sides of the main sustaining plane being arranged to revolve in one direction, and other opposed fans or blowers being arranged to revolve in the opposite direction.

2. An air ship of the heavier than air type comprising a main frame, a main sustaining plane carried by said frame and consisting of a pair of planes arranged in angular relation so as to form a V, a series of blowers on one side of said sustaining plane, a second series on the opposite side, means for operating each of said series so as to force air inwardly and from opposite directions toward said main sustaining plane, certain of said fans or blowers on one side of the main sustaining plane being arranged to revolve in one direction, and other fans or blowers being arranged to revolve in the opposite direction, and means for cutting off the air coming to the fans or blowers from the V-shaped planes, when the machine is descending.

25 3. An airship of the heavier than air type comprising a main frame, a main sustaining plane carried by said frame and consisting of a pair of planes arranged in angular relation so as to form a V, a series of blowers on one side of said sustaining plane, a second series on the opposite side, means for operating each of said series so as to force air inwardly and from opposite directions toward said main sustaining plane, certain of said fans or blowers on one side of the main sustaining plane being arranged to revolve in one direction and other fans or blowers being arranged to revolve in the opposite direction, means for cutting off the air coming to the fans or blowers from the V-shaped planes when the machine is descending, said last-named means comprising a series of curtains disposed at the outside of the fans, and a motor for operating the curtains simultaneously.

40 4. In an airship of the heavier than air type, a main frame, a main sustaining plane having portions disposed angularly with respect to one another, a series of fans or blowers adapted to force air toward said angularly disposed portions for causing the machine to rise, a car suspended from the main frame beneath the latter, a parachute comprising a pair of hinged planes disposed between said main frame and said car, and means for operating said parachute from said car.

45 5. In an airship of the heavier than air type, a main frame, a main sustaining plane having portions disposed angularly with respect to one another, a series of fans or blowers adapted to force air toward said angularly disposed portions for causing the machine to rise, a car suspended from the

main frame beneath the latter, a parachute comprising a pair of hinged planes disposed between said main frame and said car, and means for operating said parachute from said car, said last-named means comprising links pivotally connected to said hinged planes, push rods pivotally connected to said links, and means including links and levers for connecting said push rods so as to operate the latter simultaneously.

6. An airship of the heavier than air type comprising a main frame, a main sustaining plane composed of a pair of planes disposed in angular relation, fans or blowers for forcing air against said angularly disposed planes from opposite directions, an extension at the forward end of said main frame on each side of the center line, said extension being beveled to reduce the force of the wind, a front propeller disposed between said extension, and a rear propeller at the rear of the machine.

7. An airship of the heavier than air type comprising a main frame, a main sustaining plane composed of a pair of planes disposed in angular relation, fans or blowers for forcing air against said angularly disposed planes from opposite directions, an extension at the forward end of said main frame on each side of the center line, said extension being beveled to reduce the force of the wind, a front propeller disposed between said extension, a rear propeller at the rear of the machine, a front rudder immediately in rear of said front propeller, and a rear rudder immediately in the front of said rear propeller.

8. An airship of the heavier than air type comprising a main frame, a main sustaining plane composed of a pair of planes disposed in angular relation, fans or blowers for forcing air against said angularly disposed planes from opposite directions, an extension at the forward end of said main frame on each side of the center line, said extension being beveled to reduce the force of the wind, a front propeller disposed between said extension, a rear propeller at the rear of the machine, a front rudder immediately in rear of said front propeller, a rear rudder immediately in the front of said rear propeller, and means for operating both of said rudders independently.

9. An air ship of the heavier than air type comprising a main frame, a main sustaining plane carried by said frame and consisting of a pair of planes arranged in angular relation so as to form a V, a series of blowers on one side of said sustaining plane, a second series on the opposite side, means for operating each of said series so as to force air inwardly and from opposite directions toward said main sustaining plane, certain of said fans or blowers on

one side of the main sustaining plane being arranged to revolve in one direction, and other fans or blowers being arranged to revolve in the opposite direction, and individual means for cutting off the air coming to the fans or blowers from the V-shaped planes when the machine is descending, said last named means comprising a series of curtains disposed at the outside of the fans,

and an electric motor for operating the curtains simultaneously. 10
